UNITED STATES PATENT OFFICE.

HERMAN JAMES MORSE, OF RAYMOND, WASHINGTON.

AEROPLANE.

Application filed May 10, 1927. Serial No. 190,222.

The present invention relates to an aeroplane and has for its principal object to provide a structure of this nature which is more efficient and reliable than those in common use in that it enables the aeroplane to glide more freely in the air because of the shape of the top and bottom wings thereof in relation to each other.

A still further very important object of the invention lies in the provision of an aeroplane of this nature which is comparatively simple in its construction, no more expensive to build than the ordinary aeroplane, strong and durable, and easy to manipulate.

With the above and numerous other objects in view as will appear as the description proceeds, the invention resides in certain novel features of construction, and in the combination and arrangement of parts as will be hereinafter more fully described and claimed.

In the drawings:—

Figure 1 is a fragmentary side elevation of an aeroplane embodying the features of my invention,

Figure 2 is a front elevation thereof,
Figure 3 is a rear elevation thereof.

Referring to the drawings in detail it will be seen that the numeral 5 denotes a fuselage having struts 6 rising from the sides thereof and bottom wings 7 extending laterally therefrom. Other struts 8 rise from the bottom wings 7 and a top wing 9 is supported at the upper ends of these struts 6 and 8 and are thoroughly and efficiently braced by guy wires 10. Other guy wires 11 extend from the forward edge of the top wing 9 to the nose of the fuselage and preferably have incorporated therein turnbuckles 12 so that the guy wires may be maintained in a tight position.

The bottom wings 7 are braced in relation to the fuselage 5 by guy wires 13. Guy wires 14 extend from the bottom wings to the nose of the fuselage and have turnbuckles 15 therein.

Particular attention is called to the curvature of the wings 7 and 9. The wings 7 are bowed transversely having their convex surfaces disposed upwardly and their concave surfaces disposed downwardly. The wing 9 is bowed transversely but has its concave surface disposed upwardly and its convex surface disposed downwardly. Both of the wings 7 and the wing 9 have a stream line contour in side edge elevation. The partic-

ular curvature of these wings enables the aeroplane to glide most efficiently in the air as compared to the structures now in common use. These curvatures also enable the aeroplane to lift from the ground more quickly and enable the same to be more easily and efficiently handled in the air. The provision of wires or cables 11 and 14 properly brace the wings in relation to the fuselage 5 while the guy wires 10 properly brace the wings in relation to each other.

It is thought that the construction, operation, utility, and advantages of this invention will now be apparent to those skilled in this art. It is to be noted that the propeller 20 is at the nose of the fuselage and any number thereof may be used. The tail structure 21 is of suitable design including the rudder 21 and the tail ailerons 22. It is also to be noted that the fuselage 5 is of a stream line contour so as to assist in the lift of the aeroplane in conjunction with the lift of the wings 7 and 9 thus attaining a thorough cooperation between the parts.

The present embodiment of the invention has been disclosed in detail merely by way of example since in actual practice it attains the features of advantage enumerated as desirable in the statement of the invention and the above description.

It will be apparent that changes in the details of construction, in the proportion and sizes of parts and in the combination and arrangement thereof, may be resorted to without departing from the spirit or scope of the invention as hereinafter claimed or sacrificing any of its advantages.

Having thus described my invention, what I claim as new is:—

An aeroplane of the class described comprising a fuselage, a lower wing structure, an upper wing structure, said upper wing structure being bowed transversely to provide a wholly concave side facing upwardly and a wholly convex side facing downwardly, said lower wing structure being bowed transversely to provide a wholly convex surface facing upwardly and a wholly concave side facing downwardly, said wings being of fixed construction, and with their opposed longitudinal edge portions in diverged relation.

In testimony whereof I affix my signature.

HERMAN JAMES MORSE.
